CLAIM

The ornamental design for a cat tree as shown and described.

DESCRIPTION

FIG. 1 is a top, front, right side perspective view of a cat tree showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof;

FIG. 8 is an enlarged view of the portion of FIG. 2 indicated by reference numeral 8; and,

FIG. 9 is a cross sectional view of FIG. 8 taken along line 9-9 in the direction of the arrows.

The dashed broken lines illustrate portions of the article that form no part of the claimed design, and in FIGS. 2 and 8 dashed broken lines also define the bounds of enlarged views and form no part of the claimed design.
